NIKLAS F. EGLER, OF MONESSEN, PENNSYLVANIA

OPEN-HEARTH FURNACE

Application filed September 5, 1929. Serial No. 390,471.

My invention relates to open-hearth furnaces, and consists in structural provisions which may be added to a furnace of standard type with little or no interruption of operation; and which, being added, increase the serviceability of the furnace, and render the furnace adaptable to reconstruction, so far as concerns its more destructible accessory parts, and adaptable to reconstruction with little or no interruption of operation, so that the furnace may in the main be continued indefinitely in substantially uninterrupted operation. Incidentally, the invention involves the adaptation of a furnace intended for use with gas as fuel to alternative use with a "fixed" fuel, so called, such as tar or oil or natural gas.

In the accompanying drawings Fig. I is a view in vertical and longitudinal section of an open-hearth steel furnace of standard type, otherwise of familiar structure, but having added to it those features in which my invention is found. The plane of section is at the left-hand end medial, through the gas uptake; at the right-hand end the plane of section is that indicated in Fig. II by the line I—I, through an air uptake. Fig. II is a fragmentary view in approximately horizontal section, on the plane indicated by the broken line II—II, Fig. I. Figs. III and IV are views in vertical and transverse section, on the planes severally indicated by the lines III—III and IV—IV, Fig. I.

The open-hearth furnace here illustrated, in that it is of standard construction, includes the following parts: A hearth 1 with duplicate ports and accessory parts at the two ends. The gas port 2 at each end is medially arranged; and the air port 3 over-arches the gas port. At lower level are built regenerators—a gas regenerator 8 and an air regenerator 9. A slag pocket 6 is provided, which communicates with the gas regenerator 8, and a vertically arranged gas uptake 4 is provided, communicating with slag pocket 6 below and with gas port 2 above. In operation gas flows from a suitable source, a gas generator, for instance, through regenerator 8, slag pocket 6, up-

take 4, and thence through port 2 to the furnace chamber. A second slag pocket 7 is provided, which communicates with the air regenerator 9, and two vertically arranged air uptakes 5 are provided, communicating with slag pocket 7 below and with the air port 3 above. In operation atmospheric air, drawn through regenerator 9, slag pocket 7, and uptakes 5, enters the furnace chamber through port 3. These are the two lines of flow of gas and of air at the intake end of the furnace. At the outgoing end the products of combustion stream through both ports, down all three uptakes, through both slag pockets, and both regenerators, and thence off to the stack. It is deemed unnecessary to show the means by which periodically the furnace is reversed, the end which had been the outgoing end becomes in turn the intake end and the opposite end the outgoing end. These reversing means are well known. Such, in general terms, is the open-hearth furnace of standard type, to which, in the practice of my invention, structural features are added.

These added structural features are, first fuel burners, introduced through the end walls into the ports 2 at the two ends of the furnace. These burners, conventionally shown in Fig. I of the drawings, are arranged to deliver jets of fuel—oil, for instance, or tar—longitudinally through the fuel port and into the furnace chamber. They preferably are removable in such placement.

The second added structural feature is a closure for each of the two conduits through which in the standard operation outlined above gas flows alternatively from one or the other of the slag pockets 6 to the gas port. This closure advantageously takes the form of a valve 12 arranged at the upper end of the gas uptake. This valve may, conveniently, be formed of refractory material, suitably reinforced and held together by a metal frame, and it is preferably adjustable, to close the uptake entirely, or to close it to any desired degree, or, alternatively, to leave it entirely open and unobstructed.

The third and last feature, added to the

standard structure in embodiment of my invention, is a conduit through which communication is established at each end of the furnace between the air port and the slag pocket 6. This conduit is advantageously 5 constructed as shown in Figs. I and II. It there is shown to consist in vertically arranged passageways 13, duplicated on the two sides of the furnace, just as the air uptakes 5 are duplicated, built externally upon 10 the standard structure, extending immediately adjacent the two air uptakes 5 and separated, severally, from the air uptakes merely by the furnace wall. Openings are made 15 through the masonry of the standard structure through which at the upper end there is free communication between the air uptake 5 and the passageway 13, and at the lower end free communication between the slag pocket 6 and the passageway 13.

By the structural adaptation described a 20 standard furnace built for use of producer gas as fuel and having both gas and air regenerators may be transformed at slight expense, and with practically no loss in working time, to a very excellent working furnace using tar, oil, natural gas, or any similar fixed fuel, wherein it is unnecessary or 25 inadvisable to regenerate the fuel. I have 30 found that a steel furnace so reconstructed consumes a markedly less amount of fuel or B. t. u.'s per ton of steel produced than has been ordinarily considered possible heretofore.

In addition, there are in many steel plants 35 times when it becomes necessary, due to varying economic conditions, to change on short notice from producer gas to tar or oil or other fixed fuel, and vice versa. To reconstruct 40 the furnace along lines of the prior art has required not only an expenditure of relatively 45 large sums of money, but additionally the taking of the furnace out of production for several weeks or months. Obviously, when 50 tonnage is demanded, such delay can scarcely be countenanced. Moreover, with the necessity for such delays, there is danger that the economic conditions may during the time 55 of the reconstruction have changed to such extent that the purpose in view in making the reconstruction may be defeated.

In addition, another feature which presents itself to the advantage of my furnace 60 results from the fact that all furnaces, after 65 being in service for a number of heats, have the checker work in their air regenerators clogged up, thus limiting not only the draft but also the regenerative capacity of the furnace. In consequence, the time for making 70 the heat becomes longer and longer, until finally the furnace becomes so slow that it must be shut down and rebuilt, even though it would have endured for many more heats, so far as concerns the integrity of the masonry 75 and of other parts. With my invention,

a furnace which has begun to run slow may, at very slight expense and with no appreciable delay, be brought right back to proper speed. The effect is that the furnace may be operated for many more heats continuously.

In the operation of the standard furnace 80 as explained above, and leaving out of consideration the added structural features of my invention, it is obvious, from the relatively small size of the gas port 2, that at the outgoing end of the furnace a relatively small fraction of the gases will pass through the gas port 2, uptake 4, slag pocket 6, and regenerator 8; and that in consequence the checkerwork in the gas regenerators will not be heated to nearly as high a temperature as will the air regenerators. Furthermore, for the same reason, the particles of dust, ash, and slag will pass largely into the air regenerators; so that the air regenerators will become clogged up and ineffective for regenerating the incoming air, while the gas regenerators remain still clean and potentially capable of doing a great deal of effective work. And it is additionally obvious that as the air regenerators become fouled the draft through the gas regenerators will be increased and a larger fraction of the outgoing body of gas will pass through the gas regenerators.

In the operation of the furnace when modified by the structural additions described above, the valve 12 on the intake end of the furnace may be closed, and fixed fuel may be admitted through pipe or burner 14 and port 2 to the furnace chamber. No regenerated air is mixed with the fuel because uptake 4 has been closed off by valve 12. The fuel as it enters the furnace chamber mingles with regenerated air which enters through air port 3. This air has entered the furnace both from the air regenerator 9, slag pocket 7, uptakes 5, and also from the gas regenerator 8 and slag pocket 6, coming from the latter into air uptakes 5 by means of the auxiliary communicating passages 13. After passing over the charge the products of combustion leave the furnace principally through port 3, because the fuel port 2 is relatively small, and, besides, the valve 12 in its usual position is partly shut, thus throttling the flow in uptake 4. On this outgoing end the products of combustion, leaving port 3 through air uptakes 5, divide; part going directly into slag pocket 7, and through regenerator 9 to the stack, and the remainder going through auxiliary communicating passages 13, slag pocket 6, regenerator 8, and thence to the stack. If there is not enough of the products of combustion passing into these auxiliary passages 13 to heat the checkerwork in regenerator 8 to as high a temperature as in chamber 9, the valve 12 in uptake 4 is opened farther and an additional quantity of these gases then passes through port

2, uptake 4, and slag pocket 6 to regenerator 8. The valve 12 may thus be used as a regulator, to keep the checkerwork in the two regenerators at substantially equal temperatures. The result is that the incoming air for combustion (when the furnace is reversed) is heated to the highest temperature possible; a high flame temperature is attained; and, as a direct consequence, fuel consumption in B. t. u.'s per ton of steel is lowered. Preferably the passages 13 are made so large that when in the course of operation they first come into play the valve 12 on the outgoing end may be left entirely shut and still allow enough of the products of combustion to pass into slag pocket 6 and regenerator 8. Later on, as the draft becomes lessened, valve 12 may be opened more and more to effect compensation. So long as the valve 12 remains closed, the burner 14 is not exposed to outgoing gases and may be left in place; when, however, valve 12 is opened, the burner 14 should be withdrawn.

In the furnace of the prior art, designed for fixed fuel only, a single regenerative chamber at each end of the furnace is used. This is made large, to allow for the fouling of the regenerator as operation continues and still to obtain sufficient draft for the carrying away of the products of combustion. When the furnace is new, therefore, the passageway through the checkerwork in the regenerator is too large, the heat-exchanging areas too great, the bricks or tiles in the checkerwork are not brought up to a sufficiently high temperature, and, in consequence, when the furnace is reversed, the air which flows to the furnace is not heated sufficiently, the flame temperature in the furnace is low, and there is waste of fuel. Moreover, after such a furnace has been in service long enough to clog up the passages somewhat, and to reduce the heat-exchanging area, still there is no gain, because the bricks or tiles which constitute the checkerwork are then coated with less conducting material, and this prevents the outgoing products of combustion from giving up their heat to the checkerwork. When the furnace is reversed, the air still is insufficiently heated and the waste of fuel continues.

In the practice of my invention the standard furnace may initially be used in normal manner and such normal use may continue until the inevitable progressive fouling of the air regenerators will bring about the necessity of running slow. At this stage in the course of use of the furnace those ancillary parts described above may be added; and it is to be remarked that they may be added without any such interruption of operation as to involve a putting of the furnace out of service. Alternatively, the masonry which encloses the pasageways 13 may have been built before the operation began, and the valves 12

may have been provided in advance, and the burners 14 may have been made ready, and in such case all that is needed to change the furnace over to use with fixed fuel, is to knock out masonry and establish communication for the passageway 13 with the uptake 5 at its upper end and with the slag pocket 6 at its lower end, and to introduce the burner into the port 2, and, with suitable placement of the movable parts, to introduce the new fuel. Operation will continue without substantial interruption and the relatively clean regenerators 8 will then serve to heat the entering air. When then, in continued operation, the furnace begins to run slow, the air regenerator may by the bricking up or closing off of the uptakes 5 be segregated, and the so segregated regenerator may be cleaned or replaced, and this may be done with practically no loss in time, for the furnace will continue in operation, the air entering through regenerator 8, slag pocket 6 and auxiliary passages 13. If, after still further continuance of operation it be desired, the regenerator 8 may by the removing or the shutting off of the auxiliary passages 13 be segregated, the checkerwork in regenerator 8 may then be cleaned, replaced, or repaired; and, meanwhile, the furnace will continue in operation, taking air through regenerator 9 and slag pocket 7. It is evident, therefore, that by this means the furnace may be continued indefinitely in operation, so far as concerns the slag pockets and regenerators, and at all times the air for combustion as it enters the furnace may be maintained at the desired high temperature and fuel consumption may be kept at a minimum.

If at any time it is desired to go back to standard operation on producer gas or the like, this may be done with very little effort and delay, by opening or removing valves 12 and closing or removing the auxiliary communicating passages 13.

I claim as my invention:

1. In an open-hearth furnace structure of standard type including a fuel port, an air port, a fuel uptake communicating with the fuel port, an air uptake communicating with the air port, and two regenerator chambers, with each of which one of said uptakes is in communication, supplementary equipment by which the furnace may be adapted for the use of fixed fuel, such as tar and oil, such supplementary equipment including a burner in the fuel port, a valve in the fuel uptake, and a by-pass between the regenerator with which as aforesaid the fuel uptake is in communication and the air port.

2. In an open-hearth furnace structure of standard type including a fuel port, an air port, a vertically extending fuel uptake communicating at its upper end with the fuel port, a vertically extending air uptake communicating at its upper end with the air port, and two regenerator chambers arranged at

lower level than the parts named with each of which one of said uptakes is at its lower end in communication, supplementary equipment by which the furnace may be adapted for the use of fixed fuel, such as tar and oil, such supplementary equipment including a burner in the fuel port, a valve in the fuel uptake, and a passageway extending vertically from the regenerator with which the fuel uptake is in communication, and separated from the air uptake by a ported wall.

3. In an open-hearth furnace structure of standard type including a fuel port, an air port, a fuel uptake communicating with the fuel port, an air uptake communicating with the air port, and two regenerator chambers, with each of which one of said uptakes is in communication, supplementary equipment by which the furnace may be adapted for the use of fixed fuel, such supplementary equipment including a burner for fixed fuel arranged to project its flame through the fuel port to the furnace chamber, a valve in the fuel uptake adapted when closed to cut off flow through the fuel uptake, and a by-pass through which communication is established between the regenerator with which as aforesaid the fuel uptake is in communication and the air port.

30 In testimony whereof I have hereunto set my hand.

NIKLAS F. EGLER.
